(57) **CLAIM**

The ornamental design for a glove, as shown and described.

DESCRIPTION

FIG. 1 is an upper perspective view of a glove, showing our new design;

FIG. 2 is a front elevation view thereof;

FIG. 3 is a rear elevation view thereof;

FIG. 4 is a top view thereof;

FIG. 5 is a bottom view thereof;

FIG. 6 is a right side elevation view thereof; and,

FIG. 7 is a left side elevation view thereof.

The dash-dot broken lines in the drawings show portions of the glove and form no part of the claimed design. The dash-dot broken lines in the drawings illustrate the boundaries of the claim and form no part of the claimed design.

1 Claim, 4 Drawing Sheets
